CLAIM

The ornamental design for a beverage can crusher, as shown and described.

DESCRIPTION

FIG. 1 is a front, top and right side perspective view of a beverage can crusher, showing my new design;

FIG. 2 is a top plan view;

FIG. 3 is a rear elevational view;

FIG. 4 is a right side elevational view, the left side elevational view being a mirror image; and

FIG. 5 is a bottom plan view thereof.

FIG. 1

FIG. 3

FIG. 2

FIG. 4

FIG. 5
